UNITED STATES PATENT OFFICE.

HENRY P. SCHOFIELD, OF CHICAGO, ILLINOIS, ASSIGNOR OF ONE-HALF TO
L. LARSEN FILSTRUP, OF SAME PLACE.

SAW-SHARPENING MACHINE.

SPECIFICATION forming part of Letters Patent No. 574,855, dated January 5, 1897.

Application filed March 6, 1896. Serial No. 582,076. (No model.)

To all whom it may concern:

Be it known that I, HENRY P. SCHOFIELD, a citizen of the United States, residing at Chicago, in the county of Cook and State of Illinois, have invented certain new and useful Improvements in Saw-Sharpener Machines; and I do hereby declare the following to be a full, clear, and exact description of the invention, such as will enable others skilled in the art to which it appertains to make and use the same.

This invention relates to improvements in the class of automatic saw-sharpener machines, and has for its object to provide a device of this character embodying certain new and novel features in the construction, arrangement, and operation, as will be herein-after set forth in detail.

Figure 1 is a front elevation of a machine embodying my improvements; Fig. 2, an end elevation; Fig. 3, a horizontal section on line 3, Fig. 2, looking in the direction indicated by the arrow. Fig. 4 is a broken-away front elevation of a portion of the working parts, most of the supporting-frame being omitted. Fig. 5 is a plan of a shifting wheel; Fig. 6, a broken-away sectional detail on line 6, Fig. 2; Fig. 7, a part plan and part section on line 7, Fig. 2; Fig. 8, a broken-away elevation of a part of a saw, illustrating the particular-shaped tooth produced by this machine; and Fig. 9, a section on line 9, Fig. 8.

A may represent the different parts of the main frame supporting the working parts. The bar A' and parts adjustably secured to the front side of the machine serve to hold the saw in proper position during the operation of sharpening, and are adjustable with reference to saws of different diameters, a saw of the circular type being indicated by dotted lines in Fig. 1. This arrangement for holding the saw and bringing the same into position with reference to the grinding-wheel A² is not new in this class of machines, so that a detailed description will be omitted and only referred to in a general way.

In this class of machines that portion supporting the grinding or sharpening wheel is usually referred to as the "head" and comprises several different parts. The novel features of this particular head and its motion-

transmitting connections and adjusting features will be first described.

A guide-standard B is mounted on top of the frame and is rigidly secured in position. An opening B' in this guide, Figs. 1 and 7, communicates with the spout extension B², through which the waste matter from the contacting surfaces of the grinding-wheel and saw is carried away. A vertically-moving gate B³ is loosely retained in place in the rear side of the guide-standard by means of companion removable plates a a. (Shown in Figs. 2 and 7.) The lower part of the grinding-wheel gate B³ is bifurcated, so as to straddle the spout B² as a matter of convenience. The upper part of this gate terminates in a bracket extension a', in which is journaled a pivot-spindle a². The upper end of an arm a³ connects with the lower end of spindle a². On the lower end of arm a³ is formed a cap part a⁴, which forms the upper half of a journal-box for the arbor B⁴, carrying the grinding or sharpening wheel A². The part a⁵ forms the lower half of the arbor journal-box. 75

The bracket-arm extension a⁶ of the gate supports the belt guide-pulleys a⁷ a⁸, journaled therein. The belt driving the grinding-wheel is indicated in dotted lines and runs from the pulley a⁹, mounted on counter-shaft a¹⁰, down over the guide-pulleys and around pulley a¹¹ on the grinding-wheel arbor. This arrangement provides for the rotary and swinging movement of the grinding-wheel. The grinding-wheel is adapted to swing on its pivot-spindle a² just far enough in opposite directions to impart the required bevel to the cutting side of the saw-teeth. This swinging movement is transmitted and regulated by means of the following mechanism: One end 85 of a connecting-rod B⁵ is secured to the arbor journal-bearing, Figs. 1 and 2, of the grinding-wheel, as at b, the opposite end being pivoted to a plate b', as at b², the plate being in turn adjustably attached to the upper part 90 of a lever C, as shown in Fig. 2. The connecting-rod B⁵ is in two parts, which are joined by a threaded connecting-nut b³, providing for the lengthening or shortening of said rod in adjusting the same. The upper 100 end of lever C is provided with a number of holes b⁴, so that the position of plate b' may

be raised or lowered in accordance with the amount of bevel to be given to the teeth. A bracket C' is bolted to the frame and is provided with a number of holes b⁵. The lever 5 C is attached to this bracket near its longitudinal center by a pivot-pin b⁶, inserted in one of the holes, the different holes providing for the shifting of the pivotal center of the lever in regulating the throw thereof.

10 A shifting wheel C² is mounted on a counter-shaft C³, journaled in the lower part of the frame, Fig. 2. This wheel is provided in its periphery adjacent to its edges with two grooves b⁷ b⁸, Figs. 2, 3, and 5, separated by a 15 dividing-rib b⁹. These two grooves extend but a part of the way around the circumference and merge into the central groove b¹⁰ at either end. Close to one end of the rib b⁹ is located a switch-plate d, pivoted in place, as 20 at d'. The wider end of this switch-plate lies next the partition-rib and gradually narrows to the other end, stopping short of the junction of the double and single groove pathway. The upper end of a plate C¹, Figs. 2, 3, and 6, 25 is hinged, as at b¹¹, to the lower part of lever C. A friction-roller d² is journaled in the lower end of plate C¹ and is adapted to engage with and traverse the grooved passage in the shifting wheel. This wheel rotates in the direction indicated by the arrow in Fig. 5, and, 30 as shown in Fig. 3, the friction-roller d² is in the single groove and is closely approaching the switch-plate. In this position the grinding-wheel is square to and parallel with the axis of the saw being sharpened. As the 35 shifting wheel rotates, the friction-roller is diverted into the left-hand passage of the double-grooved part, which has the effect of throwing the lever end of lever C inwardly and the upper end outwardly and swinging the 40 grinding-wheel so as to bring it into position at an angle with reference to the axis of the saw and impart a beveled edge to the cutting side of the teeth, as shown at d³, Figs. 45 8 and 9. It will be noted that one corner d⁴ of the switch-plate projects into the path of the friction-roller, which, coming in contact therewith as the shifting wheel rotates, throws the switch over to the opposite position from 50 that shown, so that on the next time around the roller traverses the right-hand groove and the grinding-wheel is made to swing at the opposite angle, impart a corresponding bevel to the cutting side of the next tooth, and so 55 on alternately. During the time the friction-roller is traversing the central groove in the shifting wheel the grinding-wheel is held in a parallel position with reference to the axis of the saw and in this position has contact 60 with the back of the teeth on the up movement. This forms teeth with a square back x and adds greatly to their strength.

The teeth are sharpened and beveled on the down movement of the grinding-wheel and 65 the square back given to the teeth on the up movement, that is, when the drum-wheel is in position so that the friction-roller is in either

of the two grooves running side by side the grinding-wheel is on its down movement and is at a beveling angle. When the grinding-wheel reaches the bottom of the tooth and just before it starts on the up movement, the shifting wheel will be in position to bring the friction-roller into the single central groove and throw the grinding-wheel into its square 75 position and in contact with the back of the tooth for the up movement.

The plate C⁴ is retained in its working position by means of a pin d⁵, which on being removed will permit of the plate being turned 80 upwardly against the lever C and out of engagement with the shifting wheel, so that the grinding-wheel may be operated without the lateral swing for beveling purposes and the cutting side of the teeth formed with a square 85 face.

The grinding-wheel gate is provided on the rear side, Fig. 2, with a bearing-sleeve d⁶ for the reception of a rod D, extending downwardly therethrough. The upper end of this 90 rod is provided with a hand-wheel d⁷ and the lower end screw-threaded to engage with a lug d⁸, formed on a horizontal lever D'. One end of this lever is provided with the pivot-bearing d⁹, the opposite end terminating in the 95 handle d¹⁰, so that the grinding-wheel gate may be raised by hand when necessary so to do.

A cam-wheel D² is mounted on counter-shaft C³ and located under horizontal lever D'. A friction-roller d¹¹ is journaled to lever D 100 and has contact with cam-wheel D². Now as this cam-wheel rotates it has the effect of imparting a vertical movement to the grinding-wheel gate through the connections just described. The gate may be positioned by 105 means of the hand-rod D and the down movement limited by a screw g, inserted through horizontal lever D' and which is adapted to be adjusted so as to bottom on the frame, so that the friction-roller on lever D' may have 110 either a continuous or an intermittent contact with cam-wheel D², as the character of the work may require.

A second cam-wheel D³ is mounted on the front end of counter-shaft C³. This cam has 115 a continuous contact with a roller g', journaled in the lower end of a swinging arm D⁴, the upper end of which is pivoted to the frame, as at g⁵. A spring g⁶ presses against the lower end of arm D⁴ and serves to retain the roller 120 journaled therein loosely in contact with its cam D³. This arm is provided with a slot g⁷. A bearing-sleeve g⁸ is adjustably secured to the arm D⁴ by a bolt g⁹, inserted through slot 125 g⁷. A hand-rod E is inserted through this sleeve, the threaded end engaging with a sleeve g¹⁰, adjustably secured to feed-lever E' by means of a bolt g¹¹, inserted through a slot g¹² in said lever. The lever E' is pivoted at 130 its lower end, as at h, to the frame and provides for a reciprocating movement of the upper end, to which is pivoted one end of feed-finger F, the loose end thereof being adapted to engage with the teeth and rotate

the saw so as to bring each tooth in position to be operated upon by the grinding-wheel in the regular order of succession. By means of the swinging arm, the feed-lever, the connecting hand-rod, and the attaching parts a positive and accurate adjustment is provided, so that the movement of the saw is easily timed with reference to the movement of the grinding-wheel and also easily and quickly adjusted for saws of different diameters.

Motion is transmitted to counter-shaft C³ by means of a gear-wheel G, mounted thereon and engaging with a pinion H, mounted on a second counter-shaft H', having the band-pulley H², belting with pulley H³ on the driving-shaft.

Having thus described my invention, what I claim as new, and desire to secure by Letters Patent, is—

1. In a saw-sharpening machine, the combination with a guide-standard, having a fixed position, of a grinding-wheel gate, provided with a bracket extension and having a vertical movement in said guide-standard, a pivot-spindle, journaled in said bracket extension, the grinding-wheel and its arbor, a connecting-rod, a lever, a plate, connecting the adjacent ends of said rod and lever, and a revolute shifting wheel, adapted to impart the required movement to said lever, substantially as described.

2. In a saw-sharpening machine, the combination with a grinding-wheel and its arbor, supported from a pivotal bearing, of a rod, adjustably connecting said arbor-bearing with a lever, a lever, to which the opposite end of the rod is attached, and a shifting wheel, having a double-grooved path for a part of its

circumference and a single path running into the double path at either end, whereby the 40 grinding-wheel is set at an angle on the down movement and square with the axis of the saw on the up movement, substantially as described.

3. In a saw-sharpening machine, the combination with the grinding-wheel, of a connecting-rod, a vertical lever, a plate, having a pivotal connection with one end of said rod and adjustably attached to the upper end of said lever, a shifting wheel, provided with 50 both a double and single grooved pathway, a plate, hinged to the lower end of said lever, a friction-roller, journaled in the lower end of said plate and adapted to traverse the grooved pathway in the shifting wheel, and a switch-plate, pivoted in the shifting wheel and diverting the friction-roller alternately into one groove and then the other in imparting a swinging movement to the grinding-wheel, 55 substantially as described. 60

4. In a saw-sharpening machine, the combination with the lever, C, of a bracket, provided with a number of holes and to which said lever is adjustably attached, the shifting wheel, having grooves in its periphery as described, and the plate, hinged to the lower end of lever C and provided with a friction-roller 65 adapted to engage with the grooved periphery of said wheel, substantially as described.

In testimony whereof I affix my signature 70 in presence of two witnesses.

HENRY P. SCHOFIELD.
